UNITED STATES PATENT OFFICE.

FREDERICK M. FURBER, OF REVERE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE AND METHOD OF MAKING THE SAME.

Application filed November 24, 1917. Serial No. 203,802.

To all whom it may concern:

Be it known that I, FREDERICK M. FURBER, a citizen of the United States, residing at Revere, in the county of Suffolk and State of Massachusetts, have invented certain Improvements in Shoes and Methods of Making the Same, of which the following description, in connection with the accompanying drawings, is a specification, like referring characters on the drawings indicating like parts in the several figures.

This invention relates to the manufacture of shoes and has for its principal object to effect economies in the manufacture of welt shoes although, in certain aspects, the invention is not limited to that type of shoes. Shoes manufactured according to the welt system are recognized as the best shoes made, possessing the best appearance, giving most comfort and affording facilities for most satisfactory repair. Welt shoes are therefore worth more than other kinds of shoes, but they also cost more to manufacture, so that there continue to be many shoes made and worn which do not possess the advantages of the welt shoe. This invention substantially reduces two items of welt shoe costs so that they compare favorably with the corresponding costs in making McKay shoes.

The excellence of appearance of a Good-year welt shoe is secured in part by maintaining the shoe on its last throughout the sole laying, the sole leveling and the finishing operations. This provides that the entire sole, including its bottom, shall be shaped to the last for which the shoe was designed and shall "set" on the last, or dry sufficiently on the last, to retain permanently the shape which it was designed to have. This requires for the manufacture of each pair of shoes the use of a pair of lasts for approximately an entire week, as welt shoe manufacture is now conducted in an orderly factory. A pair of good lasts costs between one and one and a half dollars and, as the season during which a given style of last is popular is liable to be short, many welt shoe manufacturers calculate that they can average to make no more than ten pairs of shoes on a pair of lasts: in other words, that they charge off as depreciation ten percent of the cost of the pair of lasts for each of the first

ten pairs of shoes. While these figures will vary for different styles and in different factories, it will be readily seen that this system puts a very heavy "last expense" into the cost of a welt shoe. In making McKay shoes, the last is withdrawn from the shoe as soon as the shoe is lasted and is immediately available for use in making another shoe. The number of lasts required for a given daily output of a McKay factory is therefore very much less than for a corresponding output of welt shoes and the "last expense" for a McKay shoe is only a fraction of what must be charged into the costs of a welt shoe. The method of the present invention substantially reduces the time during which a pair of lasts must be used in making a pair of shoes, and therefore the "last expense" chargeable to a pair of welt shoes. This is accomplished by transferring several operations, heretofore performed while the shoe is on its last, to a different point in the shoemaking processes, where welt shoe bottoms, each comprising a sole and an attached bottom filler both shaped substantially to the curvatures of the insole, when it is fitted to the last bottom, and with or without a shank stiffener, are manufactured and preferably accumulated as complete units, ready for application to the shoe at a single operation. This procedure is effected with a substantial saving in labor because the parts of the shoe bottom can be handled and assembled with greater facility and economy by this method than when they are applied to the shoe one after another. These economies in manufacturing and accumulating welt shoe bottoms as complete units further contribute to the reduction in costs of production of welt shoes.

By this method of preparing the bottom for a welt shoe as an assembled unit applicable to the shoe in one operation, the time is saved, in the shoemaking process on the last, which was heretofore required for the five individual operations of shank attaching, application of filling material, drying of filling material, cementing of filled shoe bottom, and rough rounding of the sole after sole laying. It should be appreciated that this saving is not merely of the time actually consumed in performing

these five operations on a shoe. In a modern shoe factory system shoes go along in case lots (seventy-two pairs, or whatever the size of the case may be), each case on a rack, 5 and each operation delays the progress of the case while every one of the shoes of the case is being operated upon. The saving in time in the use of the last, therefore, is something like five times seventy- 10 two times the length of an individual operation.

This method of making welt shoes affords opportunity for securing another advantage contributing to good shoemaking and economy of production. Each sole may be and 15 preferably is prepared, as by dicing out, to have approximately the size and contour required for the size and style of the shoe of which the shoe bottom is to become 20 a part, and the bottom filler may be shaped to be inserted in the recess within the inseam of the welt shoe and may be secured to the sole with its edge in predetermined relation to the edge of the sole so that it will 25 constitute a gage by which the workman will correctly position the sole by locating the filler properly within the inseam. Advantageously also the sole is molded so that when the shoe bottom is laid upon a welted 30 shoe it conforms to the longitudinal and transverse curvatures of the last and the usual leveling or beating out operation may be dispensed with or abbreviated, as well as the usual sole rounding operation omitted. 35 Furthermore, the invention comprises other novel steps in methods of preparing shoe bottoms such as applying an adhesive and a shank stiffener to one surface of a sole and then applying a sheet filler to the adhesive and the stiffener, the parts being preferably subjected to heat and pressure to produce a unitary structure. Applicant believes himself to be the first also to unite a shank stiffener and a sheet bottom filler, 40 which is capable of developing adhesiveness under heat, by pressing them together while the stiffener is in heated condition.

Viewed in other aspects, the invention also comprehends a shoe, a bottom unit and a 45 filler, each as a novel article of manufacture. From this standpoint, the invention provides a novel welt shoe in which the outsole is relatively flatter than the insole and in which there is interposed between the soles a filler of fibrous sheet material impregnated with binding material and of varying thickness so that it substantially 55 fills the space between the soles within the inseam both laterally and vertically. Likewise, the invention provides a novel bottom unit for a welt shoe comprising an outsole molded approximately to the longitudinal and transverse curvatures of the last bottom, or of the insole when shaped to the last bottom, together with a filler attached to the 60

outsole and consisting of sheet material of varying thickness such that the filler presents a flatter surface upon its outsole engaging side than upon its reverse side. Furthermore, a novel characteristic of the 70 filler itself is that a shank stiffener is adhesively secured to and preferably embedded in the sheet material of the filler.

The invention will now be described with the aid of the accompanying drawings and 75 will then be particularly pointed out in the claims. In order to bring out clearly the features of the invention, certain elements of the shoe bottom are drawn on a somewhat larger scale than other elements. 80

Fig. 1 of the drawings is a perspective view of a shoe bottom prepared in accordance with this invention.

Fig. 1^a is a side elevation of a died-out sole requiring no rough rounding.

Fig. 2 is a transverse section on line 2—2 of Fig. 1.

Fig. 2^a represents a section on line 2^a—2^a of Fig. 1.

Fig. 3 is a longitudinal section, showing 90 a heel which may be included in the shoe bottom if desired.

Fig. 4 shows in transverse section a welt shoe which may be built in the usual way to and including the operations of attaching the welt and preparing it for the reception of the shoe bottom. This figure also illustrates the step of assembling the prepared shoe bottom, as a complete unit, with the welted shoe and accurately positioning the shoe bottom on the shoe by the aid of the filler, to present the desired projection of the sole edge at each side of the shoe so that a minimum quantity of sole leather is required and none wasted by a rough rounding operation.

In practising the method of the present invention a welt shoe is lasted or shaped over a last 2 in the usual or any suitable way and the upper is connected to the insole and a welt 3 attached by the inseam 4 as usual, after which such inseam trimming and welt beating as may be required are performed to make the shoe ready to receive its bottom. The shoe then presents 115 the condition represented in Fig. 4, there being a recess within the inseam to be occupied by the filler the function of which is to present, with the welt, a substantially continuous surface across the shoe to support the sole.

Meanwhile there will have been produced, and preferably accumulated, a quantity of the shoe bottoms wherever and under whatever conditions production can be carried 125 on to best advantage, as for example in a different department of the factory, such as the stock-fitting department, or in a separate factory. Such shoe bottoms consist of a sole 5 and a filler 6 and preferably a shank 130

stiffener 7. The sole is preferably cut, or otherwise made, to the size and shape required for the particular size and style of shoe for which it is to be used, thus economizing in leather cost and rendering unnecessary the usual rough rounding operation by which an attached sole is usually reduced to symmetrical relation to the last and thus eliminating anything more than the usual edge smoothing, or trimming, and finishing operations after the sole is stitched and leveled. The use of soles more or less cut to size has heretofore been attempted but without general success because of the difficulty and frequent failure in laying such soles on welt shoes with sufficient accuracy to enable the sole to be properly stitched to the welt, the loss from imperfect shoes having usually overbalanced the saving effected. The present invention avoids these difficulties. In the first place, the soles are preferably molded to substantially the shape desired in the finished shoe and so as to correspond to the longitudinal and transverse curvatures of the last bottom, and the cutting die is shaped to furnish a sole blank which, when distorted from its normal plane by the molding operation, will produce an accurately shaped sole presenting the correct projection from the last at every point along the edge of the sole. Such a blank is of course different in shape from the final sole shape at points and to extents to compensate for the distortion required to fit the particular style of last upon which it is to be used, these differences, and consequently the proper shape for the die, being determined for each style of last separately. After the sole blank has been molded, the filler 6 is accurately located on the molded sole.

The filler 6 may be cut from suitable sheet stock which is preferably permanently pliable, such for example as loose felt heavily impregnated with asphaltum, and is given a contour to fit approximately the recess within the inseam of the size and style of shoe of which it is to become a part. The filler may also be formed at certain points by pressure or by removal of stock so as to have a varying thickness corresponding approximately to the space at different points between the soles when assembled and it thus presents a lower face to fit the longitudinal and transverse curvatures of the last and insole and a more or less plane upper face to form with the welt a base for a sole that is to present a tread which is transversely more nearly straight than is the last bottom. The filler is accurately located on the inner or flesh face of the molded sole with the edge of the filler in predetermined relation to the edge of the sole and it is secured to the sole in such position that when it is inserted within the recess in the welted

shoe the sole connected to the filler will present the desired edge projection from the shoe.

Preferably the shank stiffener 7 is molded to the desired shape and is suitably incorporated with the sole and filler. An advantageous way of assembling the sole, stiffener and filler and of preparing the shoe bottom thus produced for attachment to the shoe consists in applying to the flesh side of the sole a coating of a suitable adhesive, such as gutta-percha, which may advantageously be a stripe of gutta-percha solution, indicated at 9 on the drawings and located a short distance inside the edge of the sole face so that it will not spread into a position where it will interfere with any edge trimming or edge finishing of the sole. It is not necessary to coat the entire surface of the sole, as shown in Fig. 1, but the gutta-percha may be applied as a stripe upon that marginal portion of the sole which is to engage with the welt and preferably extending inwardly far enough to form a connection between the filler and the sole. The gutta-percha having been applied, the shank stiffener previously heated may be preferably located on the sole face and then the filler applied in proper position and held with pressure upon the heated shank stiffener and upon the portion of the sole coated with gutta-percha until adequate adhesion of the several parts has been effected, the heat of the stiffener developing local adhesiveness in the filler into which the stiffener becomes embedded, as clearly shown in Figs. 2 and 2^a, with the result that a firm permanent connection between the two is secured. Preferably the sole is molded as a separate article previous to the assembling operation above described, and the stiffener is preferably molded to the contour of the sole. A heel 8, Fig. 3, may be included in the composite shoe bottom, if desired, and may be drilled as indicated, to facilitate attachment to the shoe from the inside, as by screws. The shoe bottom, including the sole, filler and preferably the stiffener, having been produced as described or otherwise, and preferably a quantity of shoe bottoms having been accumulated, the bottom is applied to the shoe as a unit in a single operation immediately after the welt has been attached and prepared. In applying the shoe bottom the workman uses the filler as a *gaging* means to locate the sole by introducing the filler into the recess within the inseam of the shoe as indicated in Fig. 4, and forcing the toe end of the filler firmly against the front wall of the recess. In other words, this provides for properly locating the shoe bottom by the aid of the filler. This insures that the sole will be applied or laid on its shoe so as to present the exact edge projection desired. Preparatory to laying the sole,

it will advantageously be heated to render tacky or adhesive the portion of the gutta-percha lying outside the filler so that it will adhere readily to the welt. One reason for 5 preferring to use gutta-percha is that it promptly stiffens in the atmosphere so that it is not tacky at ordinary temperatures but becomes tacky in response to a moderate degree of heat and when so warmed readily 10 adheres to the welt without necessity for coating the welt with any adhesive. Most forms of cement and glue give satisfactory results only when both of the surfaces to be connected have been coated. A convenient 15 system of handling shoe bottoms preparatory to sole laying is to magazine them in portable holders and warm each holder with its entire contents by storing it in or passing it through a warming chamber or room. 20 The shoe bottom may then be applied as described to the welted shoe and by holding it under pressure upon the shoe for a brief interval it will adhere firmly to the welt, and the shoe will then be in condition for 25 the usual stitching operation, by which the sole is permanently connected to the welt, as by the stitches 10, no preliminary or rough rounding to cut away excess sole stock being required. 30 By this method of manufacturing the shoe bottom and applying it as a unit in one operation, the time during which the last is employed in a shoe is reduced by the aggregate of time that would have been required 35 to apply the shanks to a case of shoes, transfer the case to the bottom filling station and apply the filling to the case of shoes, the two to six hours required to allow the usual bottom filling to "set," and the time required 40 for the usual sole rounding operation after the sole is laid and before it can be stitched. These operations aggregate time enough to save at least a whole day in putting shoes through the factory and in the 45 employment of the lasts, thereby making the lasts available one day sooner to be used again in making other shoes. Another important advantage for this method is that by accumulating shoe bottoms in quantities 50 ready for application to the shoes as a unit in a single operation, and thereby reducing the number of consecutive operations to be performed between welt beating and sole stitching from four or five to one, there is 55 substantially less reduction in efficiency and production by the inevitable delays in the continuous process of bottoming shoes, such for example as result from the break-down of machines, the failure of a steady supply 60 of materials, the absence of a workman and the consequent failure to keep the work moving to the next workman.

What I claim is:—

1. That improvement in methods of making welt shoes which consists in making in-

dependently two units of a shoe, one of said units comprising a connected upper, ribbed insole and welt on a last and the other unit comprising an outsole with an attached bottom filler, the outsole having approximately 70 its final contour and both outsole and filler being shaped substantially to fit the curvatures of the insole on the last bottom, and then assembling said two units accurately in final relationship by fitting the margin of 75 the filler within and against the insole rib.

2. That improvement in methods of making welt shoes which consists in preparing a welt shoe by lasting, welted and inseam trimming; preparing a shoe bottom by shaping a sole to substantially its final contour and vertical curvatures, adhesively attaching thereto a filler located to serve as a guide in placing the sole on the shoe, and incorporating with said sole and filler under heat 85 a shank stiffener; centering said bottom on the shoe by the aid of the filler; and permanently attaching said bottom to the shoe.

3. That improvement in methods of making welt shoes which consists in preparing a 90 welt shoe by lasting, welted and inseam trimming; preparing a shoe bottom, consisting of a sole, filler and shank stiffener, as a complete unit, the sole and filler being connected by adhesive; and assembling said 95 unit with the prepared shoe and permanently attaching it.

4. That improvement in methods of making welt shoes which consists in accumulating as complete units shoe bottoms each of 100 which consists of a substantially finally shaped imperforate outsole and a bottom filler attached to it; building the shoes ready for the bottoms; and applying each complete shoe bottom unit in a single operation. 105

5. That improvement in methods of making welt shoes which consists in cutting a sole substantially to its final outline, attaching thereto by adhesive a bottom filler which 110 is so contoured that it will fit the recess within the inseam of a shoe and is so located on the sole that when fitted within said recess it will position the sole properly upon the shoe, and assembling said 115 sole and attached filler with a welted shoe.

6. That improvement in methods of making welt shoes which consists in imparting to a sole approximately its final lateral contour, securing adhesively to the sole a bottom filler impregnated with asphaltic material and shaped to fit the recess within the inseam of a welted shoe, and assembling said sole and a welted shoe while using the filler as locating means to position the sole 120 in predetermined lateral relation to the welted shoe. 125

7. That improvement in methods of making welt shoes which consists in cutting a sole blank from a plane sheet of sole stock 130

- to a shape differing in size and shape from the sole finally to be produced in such respects determined for each particular style of last that when molded to fit the longitudinal and transverse curvatures of the last upon which it is to be used there will be produced a sole having substantially its final size and shape and presenting a predetermined edge projection outside the contour of
- 10 the last bottom, molding the blank to produce the shaped sole, locating a filler on the sole in position to fit the recess within the inseam of a welt shoe when the molded sole is properly located on the shoe, adhesively
- 15 securing the filler to the sole whereby the location of the filler on the sole is maintained, and assembling the sole and filler on the shoe and relatively locating the same by applying said filler to said recess in the
- 20 welted shoe.
8. That improvement in methods of making welt shoes which consists in imparting to a sole approximately its lateral contour, applying to the flesh side of the sole a coating of adhesive, superposing upon the coated surface a bottom filler shaped to fit the recess within the inseam of a welted shoe, and then applying the assembled sole and filler to the welted shoe and connecting
- 25 the sole to the welt by pressing the adhesive coated marginal surface of the sole outside the filler into engagement with the welt.
9. That improvement in methods of making welt shoes which consists in applying to the flesh side of a sole a coat of material which is adhesive when applied and will stiffen when allowed to dry but will again become adhesive upon being warmed, super-
- 30 posing a bottom filler upon the adhesive coated surface of the sole, lasting and welt-
- 35 ing a shoe, warming the adhesive coated marginal portion of the sole to render the adhesive tacky, assembling the sole and filler
- 40 upon the welted shoe and connecting the sole and welt by pressing the adhesive coated marginal portion of the sole into engagement with the welt.
10. That improvement in methods of
- 45 making welt shoes which consists in applying an adhesive to one side of a molded sole, then applying thereto a shank stiffener and also a sheet bottom filler of a shape substantially to fit within the inseam of the shoe
- 50 and then subjecting all of the parts to pressure to produce a unitary structure.
11. That improvement in methods of
- 55 making welt shoes which consists in applying an adhesive to one side of a sole, then applying thereto a shank stiffener and a sheet bottom filler of a shape substantially to fit within the inseam of the shoe and then uniting said parts firmly under heat and pressure.
- 60 12. That improvement in methods of
- making welt shoes which consists in imparting to a sole approximately its final lateral contour and its final longitudinal and transverse curvatures, locating a sheet bottom filler accurately upon the sole with
- 65 its edge in predetermined relation to the edge of the sole and adhesively uniting said parts under heat and pressure.
13. That improvement in methods of
- 70 making welt shoes which consists in imparting to a sole approximately its final lateral contour and its final longitudinal and transverse curvatures, preparing a sheet bottom filler shaped to be inserted within the inseam of the shoe and of a thickness
- 75 corresponding to the space between the soles when assembled, then assembling the sole and filler with a molded shank stiffener therebetween and adhesively uniting them
- 80 under heat and pressure.
14. That improvement in methods of
- making welt shoes which consists in applying adhesive to a sole, heating a shank stiffener and applying it to the sole, applying
- 85 a sheet bottom filler impregnated with asphaltic material to the sole over the shank stiffener and in accurate predetermined relation to the lateral contour of the sole, and then uniting said parts under heat and pressure.
15. That improvement in methods of
- making shoes which consists in providing a sheet bottom filler capable of developing adhesiveness under heat and permanently uniting the filler and a shank stiffener by pressing them together while the stiffener is in heated condition.
16. That improvement in methods of
- making shoes which consists in providing a sheet bottom filler impregnated with asphaltic material, heating a shank stiffener and then embedding it while hot in one face of the filler.
17. That improvement in methods of
- making welt shoes which consists in imparting to a sole a lateral contour and longitudinal and transverse curvatures corresponding approximately to the shape of a last bottom, molding a shank stiffener to correspond to the curvature of the sole, assembling the sole and a sheet bottom filler with the shank stiffener therebetween and adhesively uniting said parts under pressure.
18. As an article of manufacture, a bottom unit for a welt shoe comprising an outsole molded approximately to the longitudinal and transverse curvatures of a last bottom and an attached filler of sheet material and of varying thickness which is flatter on its outsole engaging side than upon its reverse side.
19. As an article of manufacture, a bottom unit for a welt shoe comprising an outsole molded approximately to the longitudinal and transverse curvatures of a last bot-

tom and having approximately its final lateral contour and a filler of sheet material and of varying thickness adhesively attached to the outsole and fitting the upper side thereof, said filler presenting at its opposite side a surface of greater curvature which corresponds closely to that of the last bottom.

20. As an article of manufacture, a bottom unit for a welt shoe comprising a molded outsole, a molded shank stiffener and a sheet bottom filler of a shape substantially fitting within the inseam of the shoe, all adhesively secured together.

15 21. As an article of manufacture, a bottom unit for a welt shoe comprising a molded outsole, a sheet bottom filler impregnated with asphaltic material and a shank stiffener located between the outsole and filler, both 20 the stiffener and filler being secured to the outsole in accurate predetermined relation to the lateral contour thereof.

22. A welt shoe having an upper, a welt, and an insole united by an inseam, an outsole relatively flatter than the insole and stitched to the welt and an intermediate filler of fibrous sheet material impregnated with binding material and of varying thickness which substantially fills the space between said soles within the inseam both laterally and vertically.

25 23. A welt shoe having an upper, a welt, an insole, a molded outsole, a sheet bottom filler substantially fitting within the inseam and having a thickness corresponding to the space between said soles, together with a 30 molded shank stiffener adhesively secured between the filler and outsole.

24. A welt shoe having an upper, a welt, 40 an insole, a molded outsole, a fibrous sheet bottom filler impregnated with asphaltic material and adhesively connected to the outsole, together with a molded shank stiffener between the filler and the outsole and in 45 a predetermined relation to the lateral contour of the outsole.

25. The method of preparing shoe bottoms which consists in applying a heated shank stiffener to a sole, and applying to the sole 50 over the stiffener a sheet filler capable of developing adhesiveness under heat.

26. The method of preparing shoe bottoms which consists in applying an adhesive and a shank stiffener to one surface of a sole, 55 and then applying a sheet filler to the adhesive and the stiffener.

27. The method of preparing shoe bottoms which consists in applying a heated shank stiffener to a sole, applying over the 60 stiffener a sheet filler capable of developing adhesiveness under heat and then subjecting all of the parts to pressure to produce a unitary structure.

28. The method of preparing shoe bottoms which consists in applying an adhesive 65

and a shank stiffener to one surface of a sole, then applying a sheet filler to the adhesive and the stiffener and then subjecting all of the parts to heat and pressure to produce a unitary structure with the stiffener embedded in the filler. 70

29. That improvement in methods of making welt shoes which comprises producing a lasted shoe with a welt attached, preparing a filler member adapted to be inserted in the recess within the inseam, shaping an outsole to approximately its final contour, attaching the filler member to the outsole with the edge contour of the filler member in such relation to the edge contour of the outsole that when the outsole is applied to the shoe with the filler member within the inseam the outsole 75 will have the desired edge projection, locating the outsole on the shoe by positioning the toe end of the filler against the front wall of the recess within the inseam, and securing the outsole to the welt. 80

30. That improvement in methods of making welt shoes which comprises producing a lasted shoe with a welt attached, preparing a filler member of varying thickness shaped approximately to fit the recess within the inseam both laterally and vertically, shaping an outsole to approximately its final contour, accurately locating the filler member on the 90 inner face of the outsole and securing it thereto in such position that when the outsole is applied to the shoe with the filler member engaging the rib of the inseam the outsole will have the desired edge projection, 100 and using the filler member as a gaging means in applying the outsole to the shoe. 95

31. That improvement in methods of making welt shoes which comprises producing a lasted shoe with a welt attached, preparing a filler member shaped to be inserted in the recess within the inseam, shaping an outsole to approximately its final contour, attaching the filler member to the outsole with the edge of the filler in predetermined relation to the 105 edge of the outsole, and using the filler member as a gaging means in locating the outsole on the shoe and thereby ensuring the desired edge projection for the outsole. 110

32. That improvement in methods of making welt shoes which comprises producing a lasted shoe with a welt attached, shaping an outsole to give it substantially the edge contour desired in the finished shoe, molding the outsole to impart to it approximately the 115 longitudinal and transverse curvatures desired in the finished shoe, preparing a filler member shaped to be inserted in the recess within the inseam, attaching the filler member to the outsole with the edge of the filler in predetermined relation to the edge of the outsole, and using the filler as a gaging means in locating the outsole on the shoe 120 and thereby ensuring the desired edge projection for the outsole. 125

33. That improvement in methods of making welt shoes which comprises producing a lasted shoe with a welt attached, shaping an outsole to give it substantially the edge contour desired in the finished shoe, securing to the outsole a shank stiffener and a filler member, said filler member being shaped to be inserted in the recess within the inseam and being attached to the outsole with the edge of the filler in predetermined relation to the edge of the outsole, and using the filler as a gaging means in locating the outsole and thereby ensuring the desired edge projection for the outsole.
34. That improvement in methods of making shoes which comprises producing a lasted shoe, preparing a shoe bottom unit by assembling an outsole, a shank stiffener and a sheet filler member of fibrous material and binding material, and subjecting the said parts of the unit with an adhesive to pressure to produce a unitary structure, then applying said unit to the shoe and fastening it thereto.
35. That improvement in methods of making welt shoes which comprises producing a lasted shoe with a welt attached, preparing a shoe bottom unit by assembling with an adhesive and in predetermined relation an outsole, a shank stiffener and a sheet filler member of varying thickness, and subjecting the said parts of the unit to pressure with heat to produce a unitary structure, then applying said unit to the shoe while using the filler member as a gaging means in locating the unit on the shoe.
36. A filler for shoe bottoms consisting of material comprising sufficient fibre to afford tensile strength, together with binding material capable of being rendered adhesive by heat, and a shank stiffener secured to the filler by the adhesion effected by heat.
37. A filler for shoe bottoms consisting of sheet material cut to fit the contour of the forepart and shank of a welt shoe bottom within the insole rib and having a shank stiffener embedded in it.
38. As an article of manufacture, a bottom unit for a welt shoe comprising an outsole having approximately its final lateral contour and approximately the longitudinal and transverse curvatures of a last bottom in combination with a sheet bottom filler adhesively secured to the outsole with its edge in predetermined relation to the edge of the outsole.

In testimony whereof I have signed my name to this specification.

FREDERICK M. FURBER.
